UNITED STATES PATENT OFFICE

132,853

DESIGN FOR AN OPEN WEB TRAILER FRAME

James Madison Foster, Memphis, Tenn.

Application July 19, 1941, Serial No. 102,296

Term of patent 14 years

To all whom it may concern:

Be it known that I, James Madison Foster, a citizen of the United States, residing in Memphis, in the county of Shelby and State of Tennessee, have invented a new, original, and ornamental Design for an Open Web Trailer Frame, of which the following is a specification, reference being had to the accompanying drawings, forming part thereof, in which:

I claim:

The ornamental design for an open web trailer frame, as shown.

JAMES MADISON FOSTER.
